(57) **CLAIM**

The ornamental design for a finish gate for drone, as shown and described.

DESCRIPTION

FIG. 1 is a first front perspective view of a finish gate for drone showing the new design.

FIG. 2 is a second front perspective view thereof;

FIG. 3 is a rear perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof;

FIG. 9 is a third front perspective view thereof; and,

FIG. 10 is a fourth front perspective view thereof.

The finish gate for drone is shown with a symbolic break in its length. The appearance of any portion of the article between the break lines forms no part of the claimed design.

1 Claim, 9 Drawing Sheets
